UNITED STATES PATENT OFFICE

MILTON M. SHAW, OF NEW YORK, N. Y., ASSIGNOR TO NEW YORK MERCHANTISE CO. INC., OF NEW YORK, N. Y., A CORPORATION OF NEW YORK

COMB AND ACCESSORIES THEREFOR

Application filed February 6, 1932. Serial No. 591,283.

This invention relates to combs and accessories therefor. It is particularly directed to a protective device for preventing the teeth of a comb from bending, breaking or becoming distorted.

An object of this invention is to provide an extremely simple and cheap protector device of the character described, adapted to be readily applied to a comb or removed therefrom, and which shall be easy to manipulate, economical to construct, attractive in appearance, durable, and yet practical and efficient to a high degree.

Other objects of this invention will in part be obvious and in part hereinafter pointed out.

The invention accordingly consists in the features of construction, combinations of elements, and arrangement of parts which will be exemplified in the construction hereinafter described, and of which the scope of the application will be indicated in the following claims.

In the accompanying drawing, in which is shown one of the various illustrative embodiments of this invention,

Fig. 1 is a side elevational view of a comb provided with an accessory embodying the invention;

Fig. 2 is a cross-sectional view taken on line 2-2 of Fig. 1;

Fig. 3 is a cross-sectional view taken on line 3-3 of Fig. 1; and

Fig. 4 is a top plan view of the blank used for making my improved protector.

Referring now in detail to the drawing, 10 designates a comb of any usual construction, having a spine or back portion 11, heavy end teeth 12 and 13, and a plurality of part-40 alle teeth 14 extending from said spine portion 11 and tapering inwardly toward the outer ends thereof. The teeth 14 are flattened and have rounded edges as in usual construction.

As is well known, combs such as comb 11, 45 are made of material such as celluloid, and the teeth 14 are flexible. In shipment or storage of these combs, the teeth often become distorted or break. For the purpose

50 of protecting the teeth against distortion,

bending, or breakage, I have provided the protector 15, comprising an elongated strip made of sheet celluloid, bakelite or any other suitable material. The protector 15 may be of U-shaped or channel-shaped cross-section, 55 and comprises a bottom wall 16 and a pair of side walls 17 and 18 extending from said wall 16. The wall 16 is formed with a row of similar slots 19 adapted to receive the tips of the teeth 14. The slots 19 are preferably 60 similar to the cross-section of the teeth 14, and are provided with rounded ends. The length of the slots 19 is preferably such that the protective member 15 may be moved only 65 a short distance beyond the tips of the teeth, for example, to the position shown in Figs. 1 and 2, the taper of the teeth acting as a stop for said protector in said position. With 70 this construction, the teeth 14 are supported adjacent the free ends thereof, and kept in spaced relation, and movement, distortion or bending of the teeth is effectually prevented. By reason of the engagement of the member 15 with the ends of the teeth, only a small 75 part of the teeth project beyond the protector, thus effectively preventing any bending movement of the ends of the teeth.

The member 15 may be made from the blank 20, shown in Fig. 4, and is first stamped to provide the slots 19 and then bent to the 80 shape shown in Fig. 2. The blank 20 is preferably transparent to permit the teeth to be seen through the protector whereby the ends of the teeth may be easily aligned with the openings 19. Obviously, where a comb is 85 made with a plurality of sets of teeth of different thickness, the protector may be formed with a row of slots, a portion of the row being adapted to receive one set of teeth, and another portion being adapted to receive another set of teeth. Preferably, the ends 21 and 22 of the protector contact the heavy end teeth 12 and 13 of the comb to prevent the ends of the protector from extending beyond 90 the comb.

It will now be understood that the protector 15 may be easily applied to or removed from the comb and will retain the teeth 14 in rigid condition.

It will thus be seen that there is provided 100

a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:—

15. 1. In combination with a comb having a plurality of teeth, a protector for said teeth comprising an elongated member having a row of openings receiving and gripping the outer ends of the teeth of said comb.
20. 2. In combination with a comb having a plurality of tapering teeth, a protector for said teeth comprising a member of channel-shaped cross-section having a wall portion formed with a row of openings receiving and gripping the outer ends of said teeth, and wall portions extending from said first wall portion and disposed on opposite sides of said comb.
25. 3. In combination with a comb having tapering teeth, a member having a plurality of openings adapted to receive said teeth, said openings being of such dimensions that the member will receive only the tips of said teeth.
30. 4. A comb comprising a back portion, a pair of substantially rigid teeth extending from the outer ends of said back portion, and a plurality of parallel, bendable teeth extending from said back portion and disposed between and in the plane of said rigid teeth, and a protector for said bendable teeth comprising an elongated member engaging said bendable teeth adjacent the outer ends thereof.
35. 5. In combination with a comb having a plurality of teeth, a protector for said teeth comprising an elongated member frictionally engaging the outer ends of said teeth.
40. 6. In combination with a comb having a back portion and a pair of parallel rigid teeth extending from the outer ends of said back portion, a plurality of parallel bendable teeth extending from said back portion and disposed between and in the plane of said rigid teeth, and a protector for said bendable teeth comprising an elongated member having a plurality of openings receiving the outer tips only of said bendable teeth, said elongated member having the outer ends thereof contacting and terminating at the inner sides of said rigid teeth.
45. 7. A comb comprising a back portion and a plurality of tapering parallel teeth extending from said back portion, said teeth being substantially of elliptical cross-section,

and a protector for said teeth comprising an elongated member made of transparent material and provided with parallel openings of substantially elliptical shape receiving the outer end portions of said teeth, the edge portions of said elongated member formed by said openings frictionally engaging said teeth adjacent the outer ends thereof for retaining said teeth in substantially rigid condition.

In testimony whereof I affix my signature.

MILTON M. SHAW.
